UNITED STATES PATENT OFFICE.

STANISLAUS KUPREL, OF BRIDGEPORT, CONNECTICUT.

AUTOMATIC APPARATUS FOR CLEANING TOBACCO-SMOKING PIPES.

1,213,215.

Specification of Letters Patent.

Patented Jan. 23, 1917.

Application filed June 29, 1914. Serial No. 848,105.

To all whom it may concern:

Be it known that I, STANISLAUS KUPREL, a subject of the Czar of Russia, residing at Bridgeport, Connecticut, have invented new and useful Improvements in Automatic Apparatus for Cleaning Tobacco - Smoking Pipes, of which the following is a specification.

This invention relates to pipe cleaners and has special reference to a device for forcing a current of air to a pipe, the device being applied to the bowl so that the air is forced out of the same.

One principal object of the invention is to provide an improved and simplified device of this character which is of such form and construction that it may be applied to the bowl of a pipe while tobacco is burning in the pipe and held tightly in position without danger of burning the fingers of the operator.

Another object of the invention is to provide an improved device of this nature wherein a more powerful air blast may be effected than is possible with devices operated by a person blowing through a tube or the like.

With the above and other objects in view as will be hereinafter apparent, the invention consists in general of certain novel details of construction and combinations of parts hereinafter fully described, illustrated in the accompanying drawings and specifically claimed.

35 In the drawing, the view is a side elevation partly in section showing the improved device as applied to a pipe.

In carrying out the objects of the invention I provide, in the present embodiment, a circular metal casing or cell A of sufficient size to entirely cover the bowl of a pipe and the under side of this cell is provided centrally with a short tubular projection —a— intended to extend downward slightly into the bowl and also form a support for a washer —a'— which is preferably made of leather or other elastic material. Extending from one side of the cell A is a tube —b— provided adjacent its extremity with a bead

—b'— so that the end of a flexible rubber tube C may be fitted on the tube —b— and securely held thereon as shown. This tube C is connected to a syringe bulb B which is of the type which when compressed forces air through the tube C and when allowed to expand draws air in through the inlet —c—. The cell A includes upper and lower parallel walls that provide an air chamber for storage of air that is filled therein by the bulb B and tube C, thereby providing a continuous pressure of air passing through the pipe P when the device is in operation.

In operation it is preferred that a charge of tobacco be placed in the pipe P and ignited. The cell A is then placed in position as shown in the figure and the bulb B repeatedly compressed and allowed to expand. This causes a flow of air through the short tube —a— and brings the tobacco in the pipe P to a bright glow much hotter than the ordinary combustion effected by smoking in the usual manner.

It is to be noted that the cell A can be held in position by the operator placing his finger thereon without danger of burning from this glowing tobacco because of the fact that there is a constant current of cool air flowing in the chamber between the upper and lower sides of the cell A thus maintaining the same cool in spite of the intense heat from the tobacco. The intense heat thus generated causes a melting of the caked products from the tobacco which has been previously smoked in the pipe and at the same time the air current blows melted products out of the stem of such pipe.

There has thus been provided a simple and efficient device of the kind described and for the purpose specified.

Having thus described the invention what is claimed is:—

A pipe cleaner comprising a circular cell having flat parallel upper and lower walls, the upper wall having a smooth and unobstructed surface and the lower wall having a short outlet tube extending from the center of the lower side of the cell, said cell forming a chamber within which air is com-

pressed, an inlet tube extending into the edge of the cell, and an elastic washer fitted on the outlet tube and covering the lower side of the cell to be seated on the upper edge
5 of a pipe to prevent the escape of air, said inlet tube being arranged for connection to the outlet tube of a syringe bulb, the inlet

tube being located entirely below the surface of the upper wall.

STANISLAUS KUPREL.
